United States Patent Office.

HORACE R. HAWKINS, OF AKRON, OHIO.

Letters Patent No. 65,568, dated June 11, 1867.

IMPROVEMENT IN LATHES FOR TURNING WOOD.

The Schedule referred to in these Letters Patent and making part of the same.

KNOW ALL MEN BY THESE PRESENTS:

That I, HORACE R. HAWKINS, of AKRON, in the county of Summit, and State of Ohio, have invented certain new and useful Improvements in the Mode of Turning Axle-Arms for Carriages, Carts, Horse-Rakes, and for similar purposes; and I do hereby declare that the following is a full, clear, and exact description of the same, reference being had to the accompanying drawing, forming a part of this specification.

The drawing represents in perspective a turning-lathe containing an axle one arm of which has been turned according to my improved mode.

The part marked A represents the frame of a turning-lathe; B, the head; C, the tail-block, and D, the gauge-turning-rest. To the spindle which is connected with the head is fastened the face-plate E, having two gauge-holes *a* *b*, and a driving dog or revolving eccentric centre *c*. After the pieces of wood or iron have been cut into proper lengths to form the axles, the pieces are placed in the lathe to turn the first arm F, in doing which the blank axle should be placed in the lathe, when the gauge-rod G is hooked into the hole *a* in the face-plate E, and care taken that the bottom side H of the axle I is up and crosswise of the stick. After the axle has been properly arranged as above stated, the first arm F is turned to a suitable size to fit the boxes for which it is intended, the lathe is then stopped, and the gauge-rod G is hooked into the hole *b* in the face-plate E, which swings the revolving or eccentric driving dog or centre *c* towards the operator, and to the same distance the other side of a vertical or perpendicular line or plane passing through the real centre of the face-plate that it occupied on the opposite side of said centre when the axle was put in to turn the first arm; the same care being taken to put the axle in bottom side up and level crosswise of the axle. After the axle has been properly arranged, the gauge-hook G is removed, and the turning of the second arm at the tail-block of the lathe completed. By the above mode of turning axle-arms, the operation is performed very expeditiously and with great uniformity of pitch and gather. The pitch may be varied to suit the length of hub and dish of wheel by moving the revolving centre or dog *c* farther from or nearer to the real centre, while the gatherer may be also changed by moving the revolving dog or centre *c* nearer to or farther from a perpendicular line passing through the real centre, when the blank axle is put in as above described, the gauge-holes *a* *b* being so arranged that the dog *c* will be swung relatively as respects the real centre as described, when the different arms are turned. By my improved method the arms of iron, as well as wooden axles, can be easily turned, and that, too, upon ordinary wood and iron turning-lathes, when provided with face-plates, gauge-rods, and eccentric or driving centres, as described and shown in the accompanying drawings. My invention renders the work of turning the arms far less complicated than when the work is performed by the ordinary modes now in use.

Having described my improvements in turning axle-arms, what I claim therein as new and of my invention, and desire to secure by Letters Patent, is—

The combination with a turning-lathe of ordinary or suitable construction of a face-plate and eccentric or driving centre under such an arrangement that the arm of the axle placed in the machine may be turned with a combined gather and pitch in the manner herein shown and specified.

HORACE R. HAWKINS.
